UNITED STATES PATENT OFFICE

REINHOLD A. NORLING, OF AURORA, ILLINOIS, ASSIGNOR TO INDEPENDENT PNEUMATIC TOOL COMPANY, OF CHICAGO, ILLINOIS, A CORPORATION OF DELAWARE

CLUTCH MECHANISM FOR POWER HOISTS

Application filed April 15, 1927. Serial No. 183,967.

This invention relates to portable power driven hoists of the type having the motor and the hoisting mechanism combined as a single assembly and thus permit handling as a single unit like any other portable power driven tool.

The invention has particular reference to the clutch mechanism which is interposed between the motor and the hoisting drum, and one object of the invention is to provide a clutch mechanism which automatically brakes or checks the descent of the load being handled, should it run ahead of the motor, and thereby prevent the load from descending except at the speed which is furnished for lowering of the load by the motor.

Another object of my invention is to have the clutch mechanism automatically tightened up by the load in raising the same and thus avoid the necessity of any manual operation to connect the load with the motor.

A further object of my invention is to have the clutch automatically stop the descent of the load should the motor stop for any reason, and thus prevent the load from dropping.

A still further object of my invention is to employ a clutch of the friction disk type and thus obtain the greatest possible holding action in the smallest possible space, as required for portable power driven hoists with the clutch mechanism simple in construction and operation, yet sturdy and strong to withstand the strains and jars of service.

The invention consists further in the matter hereinafter described and claimed.

In the accompanying drawings—

Fig. 1 is a front end view of a power operated hoist embodying the features of my invention;

Fig. 2 is a vertical longitudinal sectional view taken through the hoist on line 2—2 of Fig. 1;

Fig. 3 is an enlarged vertical sectional view taken through the clutch end of the hoist on line 3—3 of Fig. 4, the cover for the clutch mechanism being broken away for the purpose of illustration;

Fig. 4 is an end view of the clutch mechanism with the cover removed;

Fig. 5 is a transverse vertical sectional view

taken on line 5—5 of Fig. 3, with one of the friction block holders in section to show details of that structure;

Figs. 6 and 7 are opposite end views of the sleeve for the clutch disks;

Fig. 8 is a side view of said sleeve with half in section, as viewed from line 8 of Fig. 7;

Fig. 9 is a plan view of said sleeve with half in section, as viewed from line 9 of Fig. 7;

Fig. 10 is a view showing how the center clutch disk is loosely mounted on said sleeve;

Fig. 11 is a face view of one of the outer disks to show the key portions thereof for the sleeve; and

Fig. 12 is a vertical sectional view through said disk on line 12—12 of Fig. 11.

As shown in Fig. 2, the hoist comprises, generally, a motor section 1, a hoist section 2, and a clutch section 3. These sections are secured together with the motor and clutch sections 1 and 3 on opposite sides of the hoist section 2 so as to provide a balanced assembly which will hang straight and insure proper winding of the hoisting cable 4 on the drum 5 within the section 2. In the type of hoist shown, one end of the cable 4 is fixed to the case of the section 2 at 4^a (Fig. 1), while the other end of the cable is fixed to the drum 5. The loop thus provided in the cable is on the outside of the hoist below the same, and carries a pulley 6 in a hook block 7, as in devices of this kind. The hoist section 2 is provided on its upper side with a swiveled hook 2^a, by means of which the entire device may be suspended from a chain or other overhead support.

The motor within the section 1 may be of any preferred type, either electric or pneumatic, the latter being shown in the drawings. When of this type, a suitable throttle valve 8 is provided for controlling the inlet and exhaust of compressed air or other motive fluid employed to operate the motor. The valve 8 is actuated through the medium of a one-piece lever 9, which is suitably connected with the valve so as to open or close it when pulling down on the opposite ends of the lever. The latter extends across the motor section 1 to have its ends on opposite

sides thereof, and to these ends are connected handles 10, 11 by chains or other flexible elements, as shown in Fig. 1. The handles are marked "Up" and "Down," respectively, to indicate to the operator which handle must be pulled to effect operation of the motor in a direction to raise or lower a load or the pulley block 7, as the case may be. The motor will run in the direction required as long as the operator maintains his grasp on the selected handle and holds it down. On releasing a handle, a spring 9^a, associated with the lever 9, will immediately return it to its normal position, shown in Fig. 1, and close the valve 8 to cut off the supply of motive fluid to the motor and stop the same.

The crank or driving shaft 12 of the motor extends into the hoist section 2 through an interposed connecting plate 13, as shown in Fig. 2. There the shaft 12 is provided with gear teeth which mesh with a gear wheel 14 fixed to a shaft 15 which extends through and beyond the drum 5 on opposite sides thereof. A sleeve 16 is interposed between the shaft and the drum and has a tight fit in the latter and a loose mounting on the shaft, so that the shaft 15 may be rotated faster than the drum 5. The sleeve 16 extends on opposite sides of the drum and has its ends supported in the case of the hoist section 2 to support the shaft 15 and the drum 5 in said case.

The shaft 15 is extended into the clutch section 3 and has its outer end supported in the housing or cover 17 for said section, said shaft extending through the clutch mechanism in said section and supporting the same. The clutch mechanism includes a sleeve 18 loose on the shaft 15 and extending through a pair of clutch disks 19, 19 which are keyed to the sleeve in the manner shown in Figs. 6, 7, and 11. As there illustrated, the sleeve 18 is cut away to provide key-ways or recesses 20, 20 into which extend portions 21, 21 of the disks 19 so as to connect the latter with the sleeve for rotation in unison. A third disk 22 is located between the disks 19, 19 and suitable flat rings 23, 23 of friction fabric are interposed between them, so that all the disks may revolve as a unit when the disks 19, 19 are clamped against the center disk 22 with the friction material between them. As shown in Fig. 3, the friction rings 23, 23 are secured to the center disk 22 by rivets or other means, although the rings may be secured to the outer disks 19 if desired.

The center disk 22 is loosely mounted on the sleeve 18 in the manner shown in Fig. 10. The center opening 24 in the center disk 22 has a diameter as large as the outside of the sleeve 18 and thus is supported by the portions of the sleeve on opposite sides of the key-ways 20, 20, as shown in Fig. 10. In order to provide a maximum bearing surface 65 of the disks 19, 19 on the sleeve 18, I lengthen

out the key portions 21, 21 of said disks and give them an outside diameter slightly less than the diameter of the opening 24 in the center disk 22, so that said key portions 21 may enter said opening (see Fig. 3) and thus permit the disks to be arranged relatively close together and the outer disks to be moved toward and from the center disk without interference by the latter in the clamping and unclamping of the disks.

The sleeve 18 is held from endwise movement along the shaft 15 toward the motor section 1 by flange 25 on said shaft abutting against the opposed end of the sleeve 16, as shown in Fig. 2. The sleeve 16 is held from movement in this direction by a flange 16^a thereon abutting against a fixed part 2^b of the case of the hoist section 2 in which the sleeve is supported. The inner disk 19 is held from movement in the same direction along the sleeve 18 by abutting against a shoulder 26 on said sleeve.

The shaft 15 is provided with a shoulder 27 at the outer end of the sleeve 18, said shoulder being formed by reducing the portion of the shaft beyond the same, as shown in Fig. 3. A sleeve 28 is keyed or otherwise fixed to the reduced portion of the shaft 15 and is held against the shoulder 27 by a nut 29 screwed on a threaded portion of the shaft beyond the sleeve. A cotter pin may be employed for holding the nut 29 from turning after tightening the sleeve 28 against the shoulder 27. The sleeve 28 is provided with a coarse pitched thread 30 with which co-operates a 100 similarly threaded ring 31 to which is riveted or otherwise secured a pressure plate 32 carrying blocks 33, 33 of suitable friction material, such as wood, which are pressed outward by springs 34, 34 against the inner surface of 105 an overhanging annular flange 35 carried by the outermost of the friction disks 19, as best shown in Fig. 3.

The tension of the springs 34 may be adjusted through suitable screw plugs 36, 36, 110 which are carried by the plate 32 beneath the blocks 33, 33. The plate 32 is cast or otherwise formed with outwardly projecting sections 32^a, 32^a on one side thereof to support the blocks 33 and accommodate the screw 115 plugs 36 and their springs 34. A collar 37 is mounted on the coarse threaded portion 30 of the sleeve 28 at the outer side of the pressure plate 31 and carries an inwardly projecting stud 38, which lies in the path of movement of a shoulder 39 on the member 31 at one side of the stud, as shown in Fig. 4. The member 31 is cut away at 31^a on the opposite side of the stud 38 so as to provide a clearance, the purpose of which will presently 120 appear.

The outer end portion of the sleeve 28 is provided with a fine thread 40 on which is screwed a nut 41 to limit the distance that the collar 37 may travel outward on the coarse 130

thread 30. The nut 41 is held in the desired position of adjustment by a lock washer 42 and co-operating check nut 43, as shown in Fig. 3. By this construction, the outward movement of the pressure plate 32 from the friction disks 19, 22 may be regulated and the plate 32 prevented from moving farther than necessary to release the disks. Furthermore, the adjustment enables the wear on the disks 10 to be compensated for.

The center disk 22 is held from rotation in one direction by silent pawls 44, 44 engaging ratchet teeth 45 about the outer periphery of the center disk. To accommodate the teeth 15 45, the disk 22 is provided with an annular flange 46 which extends over the periphery of the inner disk 19. The pawls 44 are pivotally mounted on pins 47, which are supported at their opposite ends in the center frame 2 and the cover 17 of the hoist and clutch sections, respectively. Bands 48, 48 are connected with the pawls 44, 44 and extend part way around the outside of the flange 46. These bands are made of spring metal 20 and normally grip the outer surface of the flange, so as to have a self wrapping action thereon under a tendency to turn the disk 22 in the direction of the arrow in Fig. 4 and thus move the pawls 44 into engagement 25 with the ratchet teeth 45 to hold the disk 22 from turning in that direction. When this disk is turned in the opposite direction, it slips within the bands 48, 48 and, as the bands are given a slight movement in the same direction by reason of their frictional engagement 30 with the flange 46, the pawls 44 are swung out of engagement with the ratchet teeth 45, and thus allow the disk 22 to be turned without the pawls ratcheting over said teeth, thus providing a quiet or silent operation. The cover 17 where it extends over the pawls 44 is provided with a recess 49 to receive the pawls 44 at this time. The spring bands 48 are operatively connected with the pawls 44 by having the ends of the bands turned or bent outward at the pawls and fitting in slots 44^a provided in the pawls below their pivotal mountings 47, as shown in Fig. 4.

Two pawls 44 are provided with the pawls arranged one in advance of the other so as to lessen the amount of back lash of the disk 22 before one of the pawls engages the teeth 45. Moreover, with two pawls one pawl is sure to engage the teeth and stop the back lash of the disk in the event that the other pawl should fail. With a plurality of pawls the latter and the teeth may be made larger and thus have more strength. With the friction bands 48, 48 lying in the space between the teeth 45 and a bead 50 at the inner end of the flange 46, the pawls 44 may be made wide enough to extend over this space and thus be made stronger. The outer ends of 60 the pawls over this space are cut away so as

to clear the bands 48 as the pawls move inward to engage the teeth 45. Both pawls are made alike so that they may be interchanged, and thus avoid the necessity of being required to locate either pawl in any particular place in the assembly of the device.

The drum 5 is geared to the sleeve 18 so that the rotation of the drum in both winding and unwinding is controlled through the clutch disks 19 and 22. The connection shown in Fig. 2 comprises gear teeth 51 on the end of the sleeve beyond the inner disk 19. This end of the sleeve extends into the hoist section 2 and has its teeth 51 in mesh with a gear wheel 52 fixed to one end of a short shaft 53 which is journaled in the bearing 2^c provided therefor in the case of the hoist section 2. The other end of the shaft 53 extends to the drum 5 and has gear teeth 54 which mesh with internal gear teeth 55 provided on the drum 5.

The mechanism shown and described operates as follows. On starting the motor in the section 1 to lift a load, the motor shaft 12 is rotated anti-clockwise when viewed from the motor end of the hoist. This turns the shaft 15 clockwise through the gear wheel 14. As the shaft 15 turns with respect to the winding drum 5, the latter is held stationary by the resistance offered by the load through the cable 4. The drum 5 at this time, through its driving connection with the sleeve 18, holds the disks 19, 19 against rotation. The pressure plate 32 is also held against rotation by the frictional engagement of the blocks 33 with the flange 35 on the adjacent disk 19. As the sleeve 28 is turned with the shaft 15, its coarse thread 30, which is right-handed, causes the pressure plate 32 to be moved inward against the adjacent disk 19 and thereby effect the clamping of all the disks, which causes the sleeve 18 to be turned by the shaft 15 and rotate the drum 5 to effect the lifting of the load. The pawls 44 at this time are held up in the recess 49 and are out of engagement with the teeth 45 so that the entire clutch assembly may turn as a unit.

When the load has been lifted to the desired height, the motor is stopped upon the operator releasing the handle 10. The load at this time by its weight has a tendency to descend and turn the clutch assembly in the opposite direction. Upon the start of this movement, the spring bands 48 operate to swing the pawls 44 down into engagement with the ratchet teeth 45 and thus check the rotation and prevent further descent of the load and hold the same in that position.

To lower the load, the handle 11 is pulled and held down to reverse the motor and thus rotate the shaft 15 in the opposite direction. By this movement the sleeve 28 is turned and by its coarse thread 30 turning in a left-handed direction, the plate 32 is moved outward from the adjacent disk 19, thereby re-

130

leasing the clamping pressure on the disks and allowing the disks 19 to turn with respect to the center disk, which at this time is held stationary by the pawls 44. The stud 38 on the collar 37 is now brought into contact with the shoulder 39 and by the frictional engagement of the blocks 33 with the flange 35 the disks 19, 19 are turned with the shaft 15 to rotate the drum 5 through the sleeve 18 in a direction to lower the load by the direct action of the motor. Should the load tend to descend faster than the speed furnished by the motor, the coarse thread 30 on the sleeve 28 will cause the plate 32 to be moved inward toward the disks 19 and 15 clamp them to the now stationary disk 22, thereby checking the descent of the load. As the rotation of the shaft 15 is continued, the clamping action on the clutch disks is released or loosened by the outward movement 20 of the plate 32 so as to continue the descent of the load at the speed provided by the motor. The stud 38 is located sufficiently close to the shoulder 39 so that the inward 25 and outward movements of the member 32 are just enough to release the clamping pressure on the clutch disks and thereby prevent any sudden stopping and starting of the load. The continual turning of the shaft 15 by the 30 motor keeps releasing the clamping action between the disks, and thus allows the load to descend within the limit of the speed of the motor.

The connecting plate 13 is provided with a 35 depending lug 55 to which is pivoted a stop lever 56 having one end connected by a rod 57 to the control lever 9 so as to stop the motor upon the pulley 6 in its ascent coming into contact with the inner end of the lever 56 and raising it. This provides an automatic safety cut-off for the motor in case the operator should happen to hold the handle 11 down too long and thereby prevent the pulley 6 from being raised into contact with the 40 casing of the hoist to do damage. The air inlet for the motor is at 58.

The lost motion connection as provided by the stud 38 and the shoulder 39 allows for adjustment of the collar 37 when taking up 45 the wear between the clutch disks and, moreover, provides the clearance necessary to secure a smooth acting clutch which will take hold in both the raising and lowering of a load without any jar or strain on the mechanism or on the load on starting the motor. Furthermore, the clutch mechanism being 50 automatically tightened by the operation of the motor in turning the drum, will rotate the latter when either raising or lowering the 55 hook block 7 without any load thereon, as may be required for positioning the block to receive a load.

The details of structure shown and described with respect to the clutch mechanism 60 may be variously changed and modified with-

out departing from the spirit and scope of my invention. Moreover, the clutch disks may be increased to any number desired, depending on the amount of gripping action required for the size of hoist being made.

70

I claim as my invention:

1. In a power-driven hoist, the combination with a reversible motor and a hoisting drum, of a clutch mechanism for connecting the motor with the drum in raising and lowering a load, and screw actuated means operated by the motor when lowering the load for alternately engaging and disengaging the clutch to prevent the load from running ahead of the motor and thus be positively lowered thereby.

75

2. In a power driven hoist, the combination with a reversible motor and a hoisting drum, of a clutch mechanism for connecting the motor with the drum in raising and lowering a load, said clutch mechanism comprising friction disks, and screw actuated means operated by the motor in the lowering of the load for tightening and loosening the disks, respectively, to prevent the load from running ahead of the motor and thus be positively lowered thereby.

85

3. In a power driven hoist, the combination with a reversible motor and a hoisting drum, of a clutch mechanism for connecting the motor with the drum in raising and lowering a load, said clutch mechanism comprising friction disks, a screw turned by the motor, and a threaded member co-operating with said screw to be moved thereby toward and from said disks for tightening and loosening the same, respectively, in the turning of the motor to raise and positively lower the load thereby.

95

4. In a power driven hoist, the combination with a reversible motor and a hoisting drum, of a clutch mechanism for connecting the motor with the drum in raising and lowering a load, said clutch mechanism comprising friction disks, a screw turned by the motor, a threaded member on said screw and moved thereby toward and from the disks to tighten and release the same, respectively, in the turning of the motor to raise and lower the load thereby, and friction means acting on one of said discs for resisting the turning of the threaded member by the motor to cause the member to move endwise of the screw.

105

5. In a power driven hoist, the combination with a reversible motor and a hoisting drum, of a clutch mechanism for connecting the motor with the drum in raising and lowering a load, said clutch mechanism comprising friction disks, means for tightening and loosening the disks, respectively, in the turning of the motor to raise and lower a load thereby, and means including a pivoted pawl and ratchet teeth cooperating therewith for holding one of said disks against rotation.

115

125

130

when the motor is stopped to prevent dropping of the load.

6. In a hoist, the combination with a driving shaft, of a hoisting drum loose thereon, said shaft having a screw threaded portion at one side of said drum, a sleeve loose on said shaft and having a driving connection with the drum, friction disks keyed directly to said sleeve, a loose disk between the keyed disks, a pressure member on said screw and movable thereby toward and from the disks for tightening and loosening the same, respectively, in the turning of the shaft in opposite directions, and friction means carried by said pressure member and acting on one of the keyed disks for resisting the turning of the pressure member by said shaft.

7. In a hoist, the combination with a driving shaft, of a hoisting drum loose thereon, said shaft having a screw-threaded portion at one side of said drum, a sleeve loose on said shaft and having a driving connection with the drum, friction disks keyed directly to said sleeve, a loose disk between the keyed disks, a pressure member on said screw and movable thereby toward and from the disks for tightening and loosening the same, respectively, in the turning of the shaft in opposite directions, friction means carried by said pressure member and acting on one of the keyed disks for resisting the turning of the pressure member by said shaft, and pawl and ratchet means for holding the loose disk against rotation when the shaft is rotated to lower a load.

8. In a hoist, the combination with a driving shaft, of a hoisting drum loose thereon, said shaft having a screw-threaded portion on one side of said drum, a sleeve loose on said shaft and having a driving connection with the drum, friction disks keyed directly to said sleeve, a loose disk between the keyed disks, a pressure member on said screw and movable thereby toward and from the disks for tightening and loosening the same, respectively, in the turning of the shaft in opposite directions, and adjustable means on the shaft at the screw to limit the outward movement of the pressure member from the disks and to enable the taking up of wear of the disks.

9. In a hoist, the combination with a driving shaft, of a hoisting drum loose thereon, said shaft having fine and coarse threads at one side of the drum, a sleeve loose on said shaft and having a driving connection with said drum, friction disks keyed to the sleeve, a loose disk between the keyed disks, a pressure member on the coarse thread and having frictional engagement with one of the keyed disks, a collar on the coarse thread to limit the outward movement of the pressure member from said disks, and a lost-motion connection between the pressure member and said collar.

10. In a power driven hoist, the combina-

tion with a reversible motor and a hoisting drum, of a clutch mechanism for connecting the motor with the drum in raising and lowering a load, said clutch mechanism comprising friction disks, ratchet teeth and pawl mechanism associated with one disk for holding the same against rotation when rotating the motor in a direction to lower a load, and means operating in the rotation of the motor in the opposite direction to automatically release the pawl from the ratchet so that the disk associated therewith may turn with the motor when raising a load.

11. In a power driven hoist, the combination with a reversible motor and a hoisting drum, of a clutch mechanism for connecting the motor with the drum in raising and lowering a load, said clutch mechanism comprising friction disks, one of said disks having ratchet teeth, a pawl carried by the hoist casing, and a spring band connected with the pawl and engaging said disk in a manner to swing the pawl into and out of engagement with the ratchet teeth in the rotation of the disk in opposite directions.

12. In a power driven hoist, the combination with a reversible motor and a hoisting drum, of a clutch mechanism connecting the motor with the drum, said clutch mechanism comprising friction disks, one of said disks being loosely mounted with respect to the drum and having ratchet teeth and an annular flange on one side of the same, a pawl carried by the hoist casing to engage the ratchet teeth for holding the loose disk against rotation in one direction, and a split band gripping said flange partway about the same and having one end connected with the pawl to automatically move the same into and out of engagement with said teeth, said pawl being cut away on one side to clear the band when the pawl engages said teeth.

13. In a power driven hoist, the combination with a reversible motor and a hoisting drum, of a clutch mechanism for connecting the motor with the drum, said clutch mechanism comprising friction disks, means operated by the rotation of the motor to effect the tightening and release of the disks in the winding and unwinding of the drum, respectively, ratchet teeth on one of the disks, pawls for engaging said teeth for holding said disk against rotation when the motor is stopped and also when lowering a load thereby, a casing and a cover for the drum and clutch mechanism, respectively, and pivot pins for the pawls supported by the casing and cover, respectively.

In testimony whereof I affix my signature this 11th day of April, 1927.

REINHOLD A. NORLING.
